UNITED STATES PATENT OFFICE.

HANS O. SWOBODA, OF NEW YORK, N. Y., ASSIGNOR TO THE FALCON ELECTRIC MANUFACTURING COMPANY, OF NEW YORK.

DESIGN FOR A SWITCHBOARD.

SPECIFICATION forming part of Design No. 32,297, dated February 27, 1900.

Application filed December 15, 1899. Serial No. 740,473. Term of patent 7 years.

To all whom it may concern:

Be it known that I, HANS O. SWOBODA, a citizen of the United States, and a resident of the city, county, and State of New York, have invented and produced a certain new and original Design for a Switchboard, of which the following, in connection with the accompanying drawing, is a full, clear, and exact specification.

10 The said drawing represents a face view of a switchboard, showing my design.

15 The leading features of my design consist in the representation of a series of contact-clips concentrically arranged and a ring also concentric therewith and having a series of perforations corresponding with the number of clips, the latter being separated by spaces.

The numerals 10 and 11 denote a series of contact-clips concentrically arranged in rows

and separated from each other by spaces. 20 The clips 10, constituting one row, form separate and distinct contact-points, while the clips 11 of the other row project from an annular ring 12. Also concentrically disposed relatively to the several rows of clips is a ring 25 13, having a series of perforations 14, corresponding in number with the clips contained in one row. Index-plates, such as 15, are disposed adjacent the contact-clips of the outer row for distinguishing the same one from the 30 other.

Having described my invention, I claim—
The design of a switchboard substantially as shown and described.

HANS O. SWOBODA.
